Patented Dec. 21, 1920.

FIG. 1

FIG. 2

INVENTOR
Elmer Roland Sharp,
BY Walter N. Haskell,
his ATTORNEY

UNITED STATES PATENT OFFICE.

ELMER ROLAND SHARP, OF DAVENPORT, IOWA.

BOTTLE-CAPPING MACHINE.

1,363,170.

Specification of Letters Patent. Patented Dec. 21, 1920.

Application filed June 21, 1920. Serial No. 390,368.

To all whom it may concern:

Be it known that I, ELMER ROLAND SHARP, a citizen of the United States, residing at Davenport, in the county of Scott and State 5 of Iowa, have invented certain new and useful Improvements in Bottle-Capping Machines, of which the following is a specification.

My invention pertains to bottle capping 10 tools, and has for its purpose to provide a simple hand-operated device by the use of which metal caps or crowns can be quickly and firmly seated upon the tops of bottles, no other support for the tool being required 15 than that furnished by the bottle itself, in the operation thereof.

In the drawings:—

Figure 1 shows my device in side elevation, with one half thereof broken away, and 20 parts shown in section.

Fig. 2 is a medial longitudinal section, with the jaws of the tool in open position.

1 represents a cylindrical body member, having a crown receiving recess 2 in its 25 lower end, to which member are secured oppositely disposed arms 3. Such arms are preferably provided in pairs, spaced apart to receive the inner ends of hand-lever 4, which are pivoted between said pairs of 30 arms, as at *a*. Pivoted to the inner ends of the levers 4, as at *b*, are arms 5, the lower ends of which support semi-circular jaws 6, adapted to embrace the neck 7 of a bottle, as shown in Fig. 1.

35 The arms 3 are provided with downward projections 8, the inner edges of which are vertical and parallel, and when the arms 5 are forced inwardly and upwardly, as is accomplished by the movement of the long 40 arms of the levers 4 downwardly, the outer edges of the jaws 6 engage the inner edges of said projections, causing the jaws to move upwardly along the neck of the bottle until they are in contact with the bead on the 45 upper end thereof. A continued movement of the hand-levers forces the crown, which has been placed in position on the top of the bottle, downwardly into position thereon.

The initial movement of the hand-levers 50 4 operates to move the jaws 6 toward each other, the continued movement of the levers carrying the jaws upwardly along substantially parallel lines. At the end of the movement the pivots *b* are at a point somewhat 55 above the horizontal plane of the pivots *a*. The upward movement of the jaws 6 is lim-

ited by means of shoulders 6^a thereon which come in contact with the projections 8.

The arms 5 are further held in proper position for vertical movement by means of 60 flanges 9 thereon, against which the rounded ends of the levers 4 bear.

When the bottle has been provided with a cap, the arms 4 are again raised, swinging the jaws 6 downwardly and away from each 65 other, and permitting the tool to be removed from the bottle. To prevent the jaws from swinging outwardly too far, springs 10 are provided, coiled upon the pivots *a*, secured to the arms 4 in one direction, and having a 70 bearing against the arms 5 in the other direction. As the arms 4 are moved downwardly the tension of the springs is increased, compelling a movement of the jaws 6 between the projections 8. 75

It will be seen that the main force of the tool is exerted against the top of the bottle and the lower side of the bead thereon. On this account there is less danger of breakage of the neck of the bottle, the beaded portion thereof being the strongest part. 80

What I claim and desire to secure, is:

1. A device of the class described, comprising a body member, provided with cap seating means; supports extending from 85 said body member in opposite directions; hand-levers fulcrumed in the outer ends of said supports; and clamping members, pivotally connected with said hand-levers, and adapted to hold the head of a bottle against 90 pressure from said body member, the initial movement of said hand-levers operating to move said clamping members toward each other, and the continued movement thereof carrying said clamping members upwardly 95 along substantially parallel lines.

2. A device of the class described, comprising a body member, provided with metal cap seating means; pairs of supports extending radially from said body member; hand-levers fulcrumed in the outer ends of said supports; arms pivoted to said hand-levers, and provided with semi-circular jaws for engagement with the neck of a bottle, the movement of said hand-levers operating to 100 move said arms inwardly and upwardly; and means for holding said jaws in parallel relation during the upward movement thereof.

3. A device of the class described, comprising a cylindrical body member, provided with metal cap seating means; pairs of sup- 110

- 2
- ports extending radially therefrom, and provided with angular projections; hand-levers fulcrumed between said pairs of supports; clamping devices pivoted to said hand-levers, and adapted to be engaged by said projections to cause the movement thereof in parallel relation; and means for yieldably limiting the movement of said clamping members away from each other.
- 10 4. A device of the class described, comprising a body member, provided with cap-seating means; supports extending from said body member in opposite directions; hand-levers fulcrumed in said supports; vertically disposed arms pivoted to the inner ends of said hand-levers, and provided with flanges against which the ends of said hand-levers

bear; and clamping jaws supported by said arms, adapted to encircle the neck of a bottle.

5. A device of the class described, comprising a body member, provided with metal cap seating means; a pair of arms slideable in said body member on opposite sides of said cap seating means; complementary clamping jaws carried by said arms, adapted to encircle the neck of a bottle; and means for imparting to said arms a movement upwardly or downwardly, with a closing action of said jaws at the beginning of the upward movement, and a spreading action of the jaws at the end of the downward movement.

In testimony whereof I affix my signature.

ELMER ROLAND SHARP.
